UNITED STATES PATENT OFFICE.

WILLIAM HENRY GRIFFITH, OF NEW YORK, N. Y.

CHAIN-LINK.

SPECIFICATION forming part of Letters Patent No. 590,479, dated September 21, 1897.

Application filed April 12, 1897. Serial No. 631,794. (No model.)

To all whom it may concern:

Be it known that I, WILLIAM HENRY GRIFFITH, of New York, in the county of New York and State of New York, have invented a new 5 and useful Improvement in Chain-Links, of which the following is a specification.

This invention relates to that class or type of chain-link wherein a single piece of wire is bent to form end loops and the end portions 10 of the wire are shaped into interlocking eyes located substantially central between the ends of the link.

A chain composed of wire links constructed as heretofore and as above indicated possesses weak points and is objectionable in 15 that the extremities of the eyed portions of the wire composing each link are not both locked or tied against opposing parts of the wire body substantially at the center of the link in such manner that longitudinal tensile strains serve to clamp and tie the extremities of the eyed portions tighter and tighter 20 against such opposing parts of the wire body. The extremities of the wire are therefore 25 easily pulled out of normal position and the interlocking eyes become separated or loose, which it is very desirable to avoid.

The chief objects of my present invention are to provide a stronger and more durable 30 chain-link of the character referred to and to provide a wire chain-link having interlocking eyes which are so constructed and arranged with relation to opposing abutment-shoulders integral with the body of the wire composing 35 the link that the greater the longitudinal strain the tighter both extremities of the wire are clamped and tied against such opposing abutment-shoulders, whereby it is impossible for the two ends of the wires to pull apart or 40 become loosened, and a chain-link is provided which possesses peculiar characteristics clearly distinguishing it from all prior chain-links composed of pieces of wire of which I am aware.

To accomplish these objects, my invention 45 consists, essentially, of a chain-link composed of a single piece of wire bent into end loops and centrally between its ends having the body portion offset or shaped with reverse 50 bends forming abutment-shoulders, the end portions of the wire being formed into symmetrical interlocking eyes, each of which in-

closes and embraces both the offset portion of the middle of the wire and also the extreme end of the eye of the other loop in a reciprocal manner, whereby under longitudinal strain the said eyes respectively clamp and tie the two extremities of the wire directly against the aforesaid abutment-shoulders formed centrally in the body portion of the wire, as will hereinafter more fully appear.

The invention is illustrated by the accompanying drawings, in which—

Figure 1 is a plan view of a chain-link constructed in accordance with my invention. 65 Fig. 2 is a similar view looking at the link when turned ninety degrees or at right angles to that shown in Fig. 1, and Fig. 3 is a plan view of a modification.

In order to enable those skilled in the art 70 to make and use my invention, I will now describe the same in detail, referring to the drawings, where it will be observed that the chain-link is composed of a single piece of wire which is preferably circular in cross-section, of suitable diameter, but which may be of any desired cross-sectional form. The strip of wire is first fashioned or shaped centrally between its extremities with reverse bends for the purpose of forming or producing 75 opposing abutment-shoulders 1 and 2. The bends in this wire do not form a bight or complete convolution, but constitute a mere offset, forming shoulders. This wire strip is then shaped in any suitable manner and by 80 any machinery which will accomplish the purpose into two end loops 3 and 4, preferably somewhat elongated, but not necessarily so. The interlocking portions of the wire are bent 85 each into a complete eye 5 and 6, and each eye is made to embrace in a symmetrical and reciprocal manner both the offset middle portion of the wire and also the extreme end of the other eye—that is to say, the eye 6 embraces both the offset portion 1 2 of the middle 90 of the wire and also the extreme end 7 of the other eye, while the eye 5 embraces both the offset portion 1 2 of the middle of the wire and also the extreme end 8 of the other eye. By this construction it will be seen that the 95 terminal eye of each loop draws in the fork of the opposite loop and constricts and pinches the ends 7 and 8 against the offset 1 2, so that the greater the longitudinal tensile strain on

the link the tighter the extremities 7 and 8 will be clamped and tied against the opposing abutment-shoulders 1 and 2, forming the offset in the middle of the wire.

5 A chain-link made according to my invention, as above described, has been subjected to severe tests, which demonstrated its strength and utility and that the extremities 7 and 8 of the wire are more tightly confined after 10 excessive longitudinal strain than before.

The link shown in Fig. 3 is a modification, in which the sides of the loop are parallel and both loops lie in the same plane instead of being at right angles to each other and elliptical, as shown in Figs. 1 and 2.

I am aware that in German Patent No. 74,731 a link has been formed in which the middle of the body portion of the wire is bent into a bight or a complete convolution and the 20 ends are not formed into eyes at all, but are merely caught in the central bight or convolution. My invention is distinguished by the fact that there is no complete central convolution in the body of the wire, but only an 25 offset, and the ends of the loops are bent into completely-formed eyes, each of which completely embraces both the offset middle portion of the wire and also the extreme end of the other eye in a perfectly symmetrical and 30 reciprocal manner.

Having thus described my invention, what I claim is—

1. A chain-link composed of a single piece

of wire bent about its middle to form an offset with end loops on each side, both said 35 loops having their locking ends bent into complete eyes, and the eye of each loop embracing both the offset middle portion of the wire and also the extreme end of the eye of the other loop, both being interlocked in a sym- 40 metrical and reciprocal manner whereby the pull on each eye is made to constrict and more tightly hold the extreme end of the other eye substantially as and for the purpose de- 45 scribed.

2. A chain-link composed of a single piece of wire bent about its middle to form an offset with end loops on each side in planes at right angles to each other, both said loops 50 having their locking ends bent into complete eyes, and the eye of each loop embracing both the offset middle portion of the wire and also the extreme end of the eye of the other loop, both being interlocked in a symmetrical and reciprocal manner, whereby the pull on each 55 eye is made to constrict and more tightly hold the extreme end of the other eye substantially as and for the purpose described.

In testimony whereof I have hereunto set my hand in presence of two subscribing wit- 60 nesses.

WILLIAM HENRY GRIFFITH.
